(57) **CLAIM**

The ornamental design for a protective enclosure for transporting an automobile door, as shown and described.

DESCRIPTION

FIG. 1 is a perspective view of a protective enclosure for transporting an automobile door showing our new design, FIG. 2 is a front elevation view thereof, FIG. 3 is a back elevation view thereof, FIG. 4 is a top plan view thereof, FIG. 5 is a bottom plan view thereof; and, FIG. 6 is a left side view thereof, the right side elevation view being a mirror image of FIG. 6. The right side is symmetrical to the left side.

The broken lines shown in the figures are for the purpose of illustrating portions of the protective enclosure for transporting an automobile door and form no part of the claimed design.
